[57] CLAIM

The ornamental design for a burglar alarm, as shown and described.

DESCRIPTION

FIG. 1 is a perspective view of a burglar alarm showing our new design, with the cords broken away in the center to indicate indeterminate length;

FIG. 2 is a front elevational view thereof;

FIG. 3 is a rear elevational view thereof;

FIG. 4 is a side elevational view thereof;

FIG. 5 is a side elevational view thereof;

FIG. 6 is a top plan view thereof; and,

FIG. 7 is a bottom view thereof.

FIG. 2

FIG. 3

FIG. 6

FIG. 7

FIG. 4

FIG. 5
